Patented Apr. 17, 1917.

INVENTOR.
HOPE ALANSON.

BY *Hope Alanson* (P.S.)

UNITED STATES PATENT OFFICE.

HOPE ALANSON, OF ABBOTSFORD, BRITISH COLUMBIA, CANADA.

RAKER-GAGE.

1,222,587.

Specification of Letters Patent. Patented Apr. 17, 1917.

Application filed May 4, 1916. Serial No. 95,399.

To all whom it may concern:

Be it known that I, HOPE ALANSON, a subject of the King of Great Britain, and a resident of the town of Abbotsford, in the 5 Province of British Columbia, Canada, have invented certain new and useful Improvements in Raker-Gages, of which the following is a specification.

My invention relates to improvements in 10 raker gages, with particular reference to raker gages having straight edges faced with glass, and the object of my invention is to devise a simple and inexpensive means of securing the glass faces to the straight edge, 15 the use of which insures that the faces are always in alinement, prevents the glass from falling off, and enables a new glass to be fitted in place of a broken or damaged one.

I attain this object by the means illustrated in the accompanying drawings in 20 which—

Figure 1 is a side view of a typical raker gage showing the practical application of my device thereto.

25 Fig. 2 is a longitudinal sectional view of my device, assembled in place.

Fig. 3 is an enlarged view, in part section, of the device.

Fig. 4 is an end view of Fig. 3.

30 Fig. 5 is a view looking on the glass face.

Fig. 6 is a cross sectional view taken on the line *a—b* of Fig. 2.

Similar figures of reference indicate similar parts throughout the several views.

35 1 indicates a raker gage of a type in common use, the straight edge 2 of which is faced, on its lower side with glass. This glass face is made in two portions, these portions being disposed one on each side 40 of the opening 3, and, at present, are fastened in place to the straight edge 2 by cement or other like securing medium. With this construction, however, it is found that, in some gages, the glass faces on the opposite sides of the opening 3 are not true with each other at all points on account of the glass varying in thickness, so that the glass face is useless as a true straight edge. Further, the glass is apt to fall off if the cement 45 becomes softened or otherwise loses its tenacity, and also, should one or other of the glass faces break or become damaged, it is difficult to replace it, and thus the gage is rendered useless.

50 55 I overcome these defects by the construction shown in Figs. 3, 4 and 5, in which

4 indicates a metal casing formed as shown more particularly in Fig. 4, that is, having a flat portion 5 bent downwardly to form two sides 6 and 7, the edges of which sides 60 are bent inwardly to form flanges 8 and 9, the extreme ends of which flanges are turned upwardly, as at 10 and 11 respectively. 12 indicates a strip of glass disposed within the casing and resting on the flanges 8 and 9, which glass is normally held against longitudinal movement by the upturned ends 10 and 11 of the flanges, as shown in Fig. 3. A spring 13 is provided to keep the glass firmly pressed against the flanges, the back 70 of the spring bearing on the flat portion 5 of the casing and its ends bearing on the back of the glass. The casing 4 is open-ended, so that a broken or damaged glass may be withdrawn and a new one put in its 75 place.

In the practical application of my invention two such devices as just described are used, these being disposed one on each side of the opening 3 of the gage, as shown in 80 Fig. 1, and secured to the underside of the straight edge 2 by means of rivets 14, or other suitable means, as shown in Figs. 2 and 6.

It will now be seen that the glasses 12 85 will form a true face for the straight edge, that they cannot fall off from the gage and that a broken or damaged glass may be easily removed and as easily replaced by a new one.

90 What I claim as my invention is:

1. The combination with the straight edge of a raker gage, of a casing open at the bottom, and a strip supported wholly within the casing and unsecured thereto, said strip 95 forming a bottom for the casing.

2. The combination with the straight edge of a raker gage, of a casing open at both ends and at the bottom, a strip removably mounted within the casing and inclosed 100 thereby and forming a bottom for the same, and means within the casing for maintaining said strip in place.

3. A device of the class described, comprising a casing open at the bottom, said casing having the lower edges of its sides turned inwardly to form flanges, a glass strip mounted in said casing and resting on said flanges, and a spring within said casing disposed to bear on the said strip.

105 110 4. A device of the class described, comprising a casing open at the ends and at the

bottom, said casing having the lower edges of its sides turned inwardly to form flanges, a glass strip mounted in said casing and resting on said flanges, means for preventing inadvertent longitudinal movement of said strip, and means within said casing for maintaining the strip in detachable engagement with the said flanges.

5. A device of the class described, comprising a casing open at the ends and at the bottom, said casing having the lower edges of its sides turned inwardly to form flanges and the extremities of said flanges

turned upwardly, a glass strip resting on the said flanges between the upturned ends 15 thereof, and spring means within said casing for maintaining the said glass strip in place.

6. The combination with a glass straight edge of a raker gage, of means for holding the glass straight edge clear of the raker 20 gage, and resilient means for holding the glass in position within the supporting means.

Dated at the town of Abbotsford, B. C., this 20th day of April 1916.

HOPE ALANSON.
